UNITED STATES PATENT OFFICE.

TORANOSUKE MATSUMOTO, OF OSAKA, JAPAN.

STOVE.

Application filed February 5, 1923, Serial No. 617,000. Renewed February 28, 1925.

To all whom it may concern:

Be it known that I, TORANOSUKE MATSUMOTO, subject of the Emperor of Japan, residing at No. 2292, Tennojimura, Higashinari-gun, Osaka, Japan, have invented certain new and useful Improvements in Stoves, of which the following is a specification.

This invention relates to a stove and it provides two sets of grates one above the other the upper one supporting the freshly supplied fuel and the lower one receiving partially consumed fuel and chips or dust dropping from the upper grate, where they are burned.

The object of this invention is to secure such a combustion of fuel as will greatly conduce to economy.

Referring to the accompanying drawings:

Fig. 1 is a front elevation of the stove;

Fig. 2 is a section on the line A—B of Fig. 3;

Fig. 3 is a section on lines C—D, E—F of Fig. 1;

Fig. 4 is a section on line G—H of Fig. 2.

The corresponding numbers of reference indicate similar parts.

The stove shown has a cylindrical outer case 6 located on a base, 2, having an ash door 1. In the front side of the said outer case, is a fuel door, 7, having a damper for the admission of air to produce a down draft and a little lower an aperture, 8, for stirring the fire and further below is another door, 13. At the upper part, in the back opens a smoke flue, 9. The top part of the base, 2, has a hole, 4, and over the hole is mounted the lower grate 5, and resting on such top part is an inner case, 3. Within the inner case is set the upper grate, 10, the

interstices of which are wider than those of the lower one, 5. Below the upper grate the inner casing has draft holes, 11, made by cutting part of the inner wall between the upper and the lower grates and pressing the partially severed portions inward. The space between the inner and outer walls or cases at the fuel and ash doors is bridged as is common by passages, 12.

The operation is as follows: Smoke and flame from burning fuel on the upper grate will flow downward through the grate and pass through the vents, 11, and then ascend in the annular space formed by the outer and inner casing, walls escaping finally to the stack or chimney through the flue, 9. Cinders and chips or dust dropping from the upper grate will fall to the lower grate and there will be so perfectly burnt that they will be reduced to mere ashes. The hot products of combustion ascending in the said annular space will not only impart heat to the room by heating the outer wall, but at the same time preliminarily heat the fuel within the inner case. When the feed door is opened to put in fuel, due to the prevailing downward draft there is no danger whatever of outflow through the door, and consequently no escape of smoke or fumes to the room.

What I claim is:

A stove having an outer case and an inner case spaced apart to form a smoke passage around the inner case, an upper grate, and a lower grate that receives fuel dropping from the upper grate, the products of combustion through the smoke passage serving to preheat fuel on the upper grate.

In testimony whereof I have hereunto affixed my signature.

TORANOSUKE MATSUMOTO. [L.S.]
